SHEET TREATING APPARATUS

Adolph Langsner, Chicago, Ill., assignor to Eugene Dietzen Co., Chicago, Ill., a corporation of Delaware

Application February 9, 1938, Serial No. 189,666

7 Claims. (CL. 91—51)

My invention relates in general to sheet treating apparatus and has more particular reference to a simplified machine for transporting, while at the same time treating, sheet material with a desired treating medium which is usually a liquid; the invention having specific useful application in the treatment of light sensitive material with a liquid developing agent.

An important object of the invention is to provide simplified apparatus for applying a treating medium to sheet material, as by passing the material in contact with the surface of a roller coated with the treating medium.

Another important object of the invention is to provide improved means for causing the sheet material to pass in substantially uniform contact throughout its area with a treating roller substantially uniformly coated with the treating medium, including means to drive the sheet feeding mechanism continuously from a suitable source of power and simplified means for rapidly releasing the material being treated from the treating roller, in case of accidental jamming; a further object being to arrange the sheet feeding mechanism so that upon release thereof the treating roller is automatically disconnected from the driving means.

Another important object is to provide mechanism of the character mentioned, wherein the treating roller is not directly or positively driven by the motivating power source; a further object of the invention being to arrange the feeding and treating mechanism as a series of rollers, including at least one roller which is drivably connected with the power source, an independent sheet-treating roller, and at least one sheet-holding and power-transmitting roller shiftably mounted and adapted normally to frictionally engage the driven and treating roller, whereby to insure engagement of the material being treated with the driven and with the treating rollers, and at the same time to provide a driving connection between the driven and treating rollers, which connection may be readily interrupted merely by shifting the holding roller from its normal operating position.

Another important object is to provide a mechanism of the character mentioned, wherein the treating roller may be readily removed from operating position for cleansing, repair or replacement, without interfering with any positive driving connection.

Another important object is to provide a mechanism of the character mentioned, which is adapted to receive sheet material of any thick-

ness without requiring adjustment of the feeding or treating rollers.

Another important object resides in providing improved stripping means in an apparatus of the character mentioned for insuring release 5 of the material being treated from the treating roller at the conclusion of the treatment.

Another important object resides in mounting the sheet-guiding rollers and also the sheet-stripping means on a frame tiltable with respect to the mounting which carries the driven and treating rollers, whereby said guiding means, as well as the stripping means, may be shifted as a unit from operating position with respect to the driving and treating rollers to release the 15 material being treated and to simultaneously disconnect the treating roller from the source of driving power; a further object being to support the guiding rollers and also the stripping means with a slight, though appreciable, amount 20 of play in the tilting frame to permit the same to align themselves with respect to the treating roller when the tilting frame is moved to the operating position, whereby more particularly 25 the guiding rollers are self-adjusting to accommodate sheet material of any width in the apparatus and to assure proper stripping relationship of the stripping means upon the treating roller throughout its entire width.

Another important object is to provide a mechanism of the character mentioned, including means for applying a substantially uniform film of a suitable treating medium on the treating roller, as by means of a bath of the treating medium in which the treating roller or one or more auxiliary wetting or transfer rollers having surface contact with the treating roller is at least partially submerged; a further object being to provide improved means for maintaining the bath at a desired level with respect to the treating roller, as by providing for the continuous replenishment of the treating medium in the bath.

Another important object is to provide for 45 continuously replenishing the bath of treating medium in an apparatus of the character mentioned, including a charging funnel adapted to receive the mouth of a storage container, the charging funnel being mounted in the apparatus 50 in conveniently accessible position at an elevation to support the mouth of the storage container substantially in line with the desired level to be maintained in the bath, the invention additionally contemplating means for detachably 55

mounting the storage container in operating position with respect to the funnel.

Numerous other objects, advantages and inherent functions of the invention will become apparent as the same is more fully understood from the following description, which, taken in connection with the accompanying drawings, discloses a preferred embodiment of the invention.

Referring to the drawings,

10 Figure 1 is a perspective view of sheet-treating apparatus embodying my present invention;

Figure 2 is a similar perspective view showing the tilting frame and the guiding and stripping means carried thereby, the frame being shown 15 in released position; and

15 Figures 3, 4, 5 and 6 are sectional views taken substantially along the lines 3—3, 4—4 and 5—5, in Figure 1, and line 6—6 in Figure 5, respectively.

20 To illustrate the invention I have shown on the drawings a sheet-treating apparatus 11 comprising a main frame 13 and a tilting frame 15 carrying rollers for receiving and transporting sheet material through the apparatus, while at 25 the same time applying to the material as it is carried along a suitable treating medium supplied from a source 17.

20 The main frame 13 preferably comprises a pair of spaced-apart end pieces 19 having feet 21, the end pieces being supported and rigidly braced in spaced-apart position by means of connecting rods 23 fastened therebetween in any suitable fashion, preferably by bolting the rods onto the end pieces 19.

The end pieces may be arranged to support a roll of sheet material to be treated. This, of course, may be accomplished in any suitable or convenient fashion, although I prefer to form the end pieces as shown, with an inclined notch 25 in the forward edges of the end pieces. These notches are adapted removably to receive an axle 27 on which may be rolled and conveniently stored a quantity of sheet material 29.

The end pieces 19 are formed with journals for receiving a driven roller 31 which extends between the substantially midpoint of the upper edges of the end pieces. This roller 31 has an axle projecting outwardly of one of the end pieces 19, and means, such as the reduction gearing 33, is preferably provided for connecting the projecting shaft of the roller 31 with a suitable source of driving power which may comprise an electric motor 35 suitably mounted as on a bracket 37 secured to the end piece through which the projecting shaft of the roller 31 extends.

The end pieces also are formed with bearings for a following roller 39 positioned immediately above and parallel with respect to the driven roller 31, the bearings of the roller 39 being formed with sufficient play to permit the roller 39 to rest by gravity upon the roller 31, the rollers being adapted to separate to permit sheet material of any width to pass therebetween.

An inclined, preferably sheet metal plate 41 forming a sheet-feeding surface is secured between the end pieces 19 along the upper edges thereof in front of the rollers 31 and 39, so that material to be treated may be pushed across the feeding surface of the plate 41 and guided between the rollers 31 and 39. The material thus fed may be a continuous strip drawn from the roll of material 29 or may be individual sheets, manually or otherwise delivered across the table 41 to the feeding rollers 31 and 39.

Rearwardly of these feeding rollers the end pieces 19 are formed with notches 43 in the upper edges of the pieces 19. The notches 43 are in alignment transversely of the frame 13 and serve to receive the axles 45 projecting at the ends of a treating roller 47 which is thus supported for rotation in the main frame in a fashion permitting ready removal of the roller 47 from mounting position by merely lifting it upwardly to raise the axles 45 from the slots 43.

Beneath the roller 47 the frame carries means forming a trough 49 adapted to receive a preferably liquid sheet-treating medium 51 which is maintained at a desired level in the trough 49. Any suitable arrangement may be employed to 15 apply the treating medium as a substantially uniform film upon the treating roller 47, and in the illustrated embodiment this is accomplished by positioning the trough 49 so that the lower portions of the roller 47 are immersed in the bath 20 of liquid 51. To this end, the pieces 19 are formed on their inwardly facing surfaces with support means 53 adapted to receive the opposite ends of the trough 49 and support the same in the desired position with respect to the 25 roller 47.

I also provide means for continuously delivering the liquid-treating medium 51 to the trough in order to maintain a desired liquid level therein, and, as shown, the trough is provided with a 30 charging conduit 55 opening, preferably, into the bottom of the trough 49 and extending thence through a suitable opening formed in one of the end pieces 19. Outwardly of said end piece the conduit 55 is connected in any suitable fashion 35 with a charging funnel 57 which is supported in a bracket 59 on the end piece 19.

The funnel 57 internally is formed with projections 61 forming one or more upwardly facing shoulders 63, the funnel being supported in 40 the bracket 59 at an elevation such that the shoulders 63 are in approximate alignment with the liquid level to be maintained in the trough 49.

The end piece 19 also carries a bracket 65 45 forming a clip for receiving and supporting the supply source 17 on the main frame of the device. The supply source, of course, may have any suitable form, but I prefer to employ a common bottle, the support clip 65 being adapted to firmly receive the lower portions of the bottle in order to support the same with its neck extending in the funnel 57 in position resting upon the shoulder 63. A container, such as a bottle supported in this fashion, will maintain the desired level of liquid in the trough 49 as long as the bottle itself contains any liquid. When the bottle becomes empty, it may easily be removed from the clip 65 and replaced with a full bottle 50 without interrupting the operation of the apparatus.

Material delivered between the rollers 31 and 39 will be carried thence and delivered into contact with the roller 47. Since there is no direct positive connection between the roller 47 and 65 the driving means 35, the roller 47 may be quickly and easily removed from operating position for the purpose of cleaning the same or for repair or replacement. When the apparatus is in operation, however, I desire to connect the roller 47 70 so that it may be driven at the same peripheral speed at which the rollers 31 and 39 are rotated by the motor 35. To this end and, further, to insure that the sheet material being treated is maintained in substantially uniform contact with 75

the treating roller 47 during its passage there-over, I form the tilting frame 15 with a sheet-guiding roller 67 which, when the frame is in the elevated position shown in Figure 2, is disconnected from the driven roller 31 as well as the treating roller 47, the frame being arranged, when in elevated position, to support the roller 67 in a position permitting the roller 47 to be removed from mounted position for the purposes heretofore mentioned. The tilting frame 15, however, may be lowered to a position in which the roller 67 rests firmly upon the surfaces of the rollers 31 and 47, and thereby provides a driving connection between the driven roller 31 and the treating roller 47. The roller 67 also functions when in operating position to direct the material being treated from the roller 31 and onto the roller 47.

I also prefer to provide an additional roller 69 20 in the tilting frame 15, said roller 69 being parallel and adjacent with respect to the roller 67 and in position to rest upon the surface of the roller 49 when the frame is in operating position. The roller 69 serves to maintain the material being treated in contact with the treating roller throughout a substantial area of said treating roller.

Since the treating medium 51 is preferably and usually a liquid, the sheet material may have a 30 tendency to adhere upon the surface of the treating roller. To prevent this tendency from carrying the sheet material around the roller and through the bath 49, I provide stripping means 71.

The stripping means comprises a plurality of 35 spaced lifting fingers adapted to bear upon the surface of the roller 47 at intervals throughout the width of the treating roller, in order to insure separation of the sheet material being treated at the termination of the period of treatment 40 on contact on the roller. Since I wish to provide for the ready removal and replacement of the roller 47 for the reasons heretofore stated, I arrange the spaced fingers comprising the lifting means in the tilting frame 15 so that 45 these fingers may be entirely released and removed from the roller 47 when the tilting frame is elevated.

To this end the tilting frame 15 comprises a shaft 73 which is journaled at its opposite 50 ends in bearings formed in the upper, rearward corner portions of the end elements 19, the opposed ends of the shaft 73 preferably projecting outwardly of the end pieces 19 and receiving each an end member 75 of the frame 15. These 55 end members 75 provide bearings for the rollers 67 and 69, and also are interconnected by means of a bar 77 secured in place on the members 75 in any suitable fashion, as by cotter-pins 79.

The fingers forming the lifting means 71 preferably 60 comprise sheet metal stampings 81 having pointed tips 83 at one end thereof for the purpose of riding upon the surface of the roller 47 to separate the sheet material from the roller when it reaches said pointed ends of the fingers 65 81. The ends of the fingers 81 opposite from the sheet lifting portions are notched, as at 85, to receive the shaft 73 of the tilting frame, said shaft being grooved at intervals, as at 87, to receive the notched ends 85 of the sheet-lifting 70 fingers and to prevent displacement of said notched ends axially on the shaft 73.

Between their opposed ends the fingers 81 are provided with openings 89, through which the shaft extends, in order to maintain the fingers 75 81 in proper alignment in the frame and to raise

the same from the roller 47 when the frame is moved to the elevated or inactive position. The fingers 81, however, are relatively loosely mounted on the rod 77 in order that when the frame is in depressed or operating position the pointed ends of the fingers may rest upon the surface of the treating roller 47 in order that the fingers may each be self-aligning and press upon the roller under the influence of its own weight. In order to facilitate manipulation of the tilting frame 15, the end pieces 15 thereof may be formed with handles 91.

The rollers 31, 39, 47, 67 and 69 may, of course, be of any suitable or convenient construction. I prefer, however, to form the rollers 31, 39, 67 15 and 69 as solid cylindrical rods with stub axles 92, preferably of metal secured to the opposite ends of the rollers in any suitable or convenient manner, as by forming teeth on the stub axles and driving such formed portions into sockets formed 20 in the opposed ends of the rollers. The treating roller, however, which is of relatively large diametral dimension, preferably comprises a cylindrical roller element of any suitable material, such as Bakelite, the opposite ends of the cylindrical element being fitted with preferably aluminum fittings forming stub axles. These fittings, as shown, preferably comprise an end 93 formed with surface flutes 95 adapted to be forced into the end of the cylindrical member to form a 30 splined connection therewith.

The end fitting adjacent the fluted portion is formed preferably with an annular collar 97 adapted to abut the end of the cylindrical element in which the fitting is mounted. Outwardly of the collar 97 the fitting is preferably of restricted diameter forming a groove adapted to receive the end edge of the trough 49, the fitting beyond the groove being formed as a stub axle 99 for mounting in the main frame 13. 40

It will be noted that the axles at the opposed ends of the rollers 31, 39, 67 and 69 are generally similar to the axle fittings utilized at the ends of the treating roller 47. It is, of course, essential that the medial portions of the rollers 67 and 69 45 actually contact with the medial portions of the driven and treating rollers. In fact, I prefer to separate the rollers slightly, as shown, by providing friction bands 101 upon the end fittings 92 of the rollers 67 and 69. These friction bands 50 may be of rubber-like material or other suitable friction material having good wearing qualities, and they are adapted to rest upon the shoulders 98 formed on the end fittings of the treating roller when the tilting frame is in the lowered or operating position, in order to drivingly connect the rollers 67 and 69 with the treating roller and support the surfaces of the guiding elements in position slightly spaced with respect to the surface of the treating roller. The friction bands 101 also 55 serve, when the frame 15 is in operating position, to frictionally connect the roller 67 with the driven roller 31 since the friction bands of the roller 67 are arranged to ride upon the end fittings 60 of the driven roller.

The sheet-treating apparatus of my present invention is relatively simple and inexpensive to make. It is, however, positive and automatic in action and will successfully accommodate sheets of any thickness, provided the material is sufficiently flexible to travel the somewhat serpentine path between the rollers 31, 47, 67 and 69. The apparatus also is simple from an operating standpoint, and affords, among others, the advantage of a readily removable treating roller 47 which 70

does not require disassembly of driving connections in order to permit removal of the roller for inspection, cleaning, repair or replacement. At the same time, the apparatus provides guiding rollers for insuring that the material being treated travels the desired pathway across the treating roller, and also simple and inexpensive, yet positively acting, stripping means for insuring the release of the material from the treating roller after the completion of the treating process. These stripping fingers, however, do not in any way interfere with the ready removability of the treating roller for the purpose heretofore mentioned.

15 The driving and guiding roller is self-aligning and not only insures the delivery of the sheet material to the treating roller, but also insures that the treating roller is driven at the same peripheral speed as the sheet-feeding roller 31.

20 The apparatus also provides for a continuous and ample supply of the liquid treating medium 51 by virtue of the improved means for maintaining a desired liquid level in the trough 49 from a remote and readily renewable source of supply 17.

30 It is thought that the invention and numerous of its attendant advantages will be understood from the foregoing description, and it is obvious that numerous changes may be made in the form, construction, and arrangement of the several parts of the illustrated apparatus without departing from the spirit or scope of my invention or sacrificing any of its attendant advantages, the forms herein described being merely for the purpose of illustrating the invention.

35 The invention is hereby claimed as follows:

1. Sheet treating apparatus comprising a main frame, a driven roller on said frame for delivering sheet material along a predetermined path, a 40 treating roller mounted in said frame and spaced from the driven roller in position to receive sheet material from the driven roller, said treating roller being readily removable from said frame, and a guiding roller shiftable on said frame and adapted 45 normally to engage the driven and the treating roller whereby to guide sheet material from the driven roller to the treating roller and to form a driving connection with the driven roller and with the treating roller, said guiding roller serving al- 50 so to retain the treating roller in operative position on said frame and being shiftable to drivingly disconnect the driven and treating rollers and to release said treating roller for removal from the frame.

55 2. Sheet treating apparatus comprising a main frame, a driven roller on said frame for delivering sheet material along a predetermined path, a treating roller mounted in said frame and spaced 60 from the driven roller in position to receive sheet material from the driven roller, said treating roller being readily removable from said frame, a guiding roller shiftable on said frame and adapted 65 normally to engage the driven and the treating rollers whereby to guide sheet material from the driven to the treating roller and to form a driv- 70 ing connection with the driven roller and with the treating roller, and a holding roller, remote from the guiding roller in position, normally to cooperate with the surface of the treating roller to retain sheet material thereon during treat- 75 ment, said guiding and holding rollers serving to retain the treating roller in operative position on the frame and being shiftable to release said treating roller for removal from said frame and

to drivingly disconnect the driven and treating rollers.

3. Sheet treating apparatus comprising a main frame, a driven roller on said frame for delivering sheet material along a predetermined path, a 5 treating roller mounted in said frame and spaced from the driven roller in position to receive sheet material from the driven roller, said treating roller being readily removable from said frame, and a guiding roller shiftable on said frame and adapted 10 normally to engage the driven and the treating rollers whereby to guide sheet material from the driven roller to the treating roller and to form a driving connection with the driven roller and with the treating roller, said guiding roller serving also 15 to retain the treating roller in operative position on said frame and being shiftable to drivingly disconnect the driven and treating rollers and to release said treating roller for removal from the frame, wherein at least one of said rollers com- 20 prise solid, cylindrical elements having separate fittings splined in sockets formed in the opposed ends of said members, said fittings having projecting portions forming axles.

4. Sheet treating apparatus comprising a main 25 frame, a driven roller on said frame for delivering sheet material along a predetermined path, a treating roller mounted in said frame and spaced from the driven roller in position to receive sheet material from the driven roller, said treating roller being readily removable from said frame, and a guiding roller shiftable on said frame and adapted 30 normally to engage the driven and the treating rollers whereby to guide sheet material from the driven roller to the treating roller and with the treating roller, said guiding roller serving also to retain the treating roller in operative position on said frame and being shiftable to drivingly disconnect the driven and treat- 35 ing rollers and to release said treating roller for removal from the frame, wherein at least one of said rollers comprises a cylindrical shell element having separate fittings splined in sockets formed in the opposed ends of said members, said fittings having 40 projecting portions forming axles.

5. Sheet treating apparatus comprising a main frame, a driven roller on said frame for delivering sheet material along a predetermined path, a treating roller mounted in said frame and spaced from the driven roller in position to receive sheet material from the driven roller, said treating roller being readily removable from said frame, and a guiding roller shiftable on said frame and adapted normally to engage the driven 55 and the treating rollers whereby to guide sheet material from the driven roller to the treating roller and to form a driving connection with the driven roller and with the treating roller, said guiding roller serving also to retain the treating roller in operative position on said frame and being shiftable to drivingly disconnect the driven and treating rollers and to release said treating roller for removal from the frame, the driving 60 connection between the driven, treating and guiding rollers comprising bands frictionally secured on and at the opposite ends of said guiding roller in position to form frictional driving engagement with the driven and treating rollers at the ends thereof when said guiding roller is in operative 65 position.

6. Sheet treating apparatus comprising a main frame, a driven roller on said frame for delivering sheet material along a predetermined path, a treating roller mounted in said frame in position 70

to receive sheet material from the driven roller, said treating roller being readily removable from said frame, and a guiding roller shiftable on said frame and adapted normally to engage the driven 5 and the treating rollers whereby to guide sheet material from the driven roller to the treating roller and to form a driving connection between the driven and the treating rollers, said guiding roller serving also to retain the treating roller in operative position on said frame and being shiftable to drivingly disconnect the driven and treating rollers and to release said treating roller for removal from the frame, and driving means on at least one of said rollers in position to provide frictional driving engagement between the several 10 rollers when said guiding roller is in operative position, said treating and guiding rollers being drivingly actuated only from said driven roller.

7. Sheet treating apparatus comprising a main 15 frame, a driven roller on said frame for delivering sheet material along a predetermined path, a treating roller mounted in said frame in posi-

tion to receive sheet material from the driven roller, said treating roller being readily removable from said frame, and a guiding roller shiftable on said frame and adapted normally to engage the driven and the treating rollers whereby 5 to guide sheet material from the driven roller to the treating roller and to form a driving connection between the driven and the treating roller, said guiding roller serving also to retain the treating roller in operative position on said frame and 10 being shiftable to drivingly disconnect the driven and treating rollers and to release said treating roller for removal from the frame, means on the ends of said rollers forming projecting axles, and driving means on the said axles of at least one of 15 said rollers in position to provide frictional driving engagement between the axles of the several rollers when said guiding roller is in operative position, said treating roller and said guiding roller being drivingly actuated only from said driven 20 roller.

ADOLPH LANGSNER.
